(57) **CLAIM**

We claim the ornamental design for a shoe with injected pattern design, as shown and described.

DESCRIPTION

FIG. 1 is a right side elevational view of a shoe with injected pattern design, according to the present invention;

FIG. 2 is a left side elevational view of the shoe with injected pattern design;

FIG. 3 is a top plan view of the shoe with injected pattern design;

FIG. 4 is a bottom plan view of the shoe with injected pattern design;

FIG. 5 is a front elevational view of the shoe with injected pattern design;

FIG. 6 is a rear elevational view of the shoe with injected pattern design; and,

FIG. 7 is a front top left perspective view of the shoe with injected pattern design.
